United States Patent Office

Des. 220,647
Patented May 4, 1971

220,647

INCLINOMETER

Richard M. Provi, 1907 Brownfield Road 61107, and
Donald L. Payne, 4849 Danforth Drive 61111, both
of Rockford, Ill.

Filed June 22, 1970, Ser. No. 23,583

Term of patent 14 years

Int. Cl. D10—08

U.S. Cl. D52—6

FIG. 2

FIG. 3

FIG. 1

FIG. 4

FIG. 5

FIG. 6

FIG. 1 is a front elevational view of an inclinometer showing our new design; and

FIG. 2 is a top plan view thereof; and

FIG. 3 is a left side elevational view thereof; and

FIG. 4 is a right side elevational view thereof; and

FIG. 5 is a bottom plan view thereof; and

FIG. 6 is a rear elevational view.

We claim:

The ornamental design for an inclinometer, as shown.
